UNITED STATES PATENT OFFICE.

WILLIAM J. NOBLE, OF NEW YORK, N. Y.

DESIGN FOR A BURIAL-CASKET TOP.

SPECIFICATION forming part of Design No. 18,030, dated January 24, 1888.

Application filed November 16, 1887. Serial No. 255,370. Term of patent 7 years.

To all whom it may concern:

Be it known that I, WILLIAM J. NOBLE, of the city, county, and State of New York, have invented a new and original Design for Burial-Casket Tops, of which the following is a full, clear, and exact description.

My invention relates to a design for the tops or lids of burial-caskets or coffins; and it consists, essentially, in a burial-casket top provided with posts upon its top and a rail passing from post to post entirely around the casket-top, as hereinafter particularly described and claimed.

Reference is to be had to the accompanying drawing, forming a part of this specification, and which is a perspective view of a casket-top embodying my design, and set in inclined position.

In executing my design I provide the casket-top with a rail, A, which is held to posts B upon the casket-top. The rail passes from post to post about parallel with the top surface of the casket-lid.

The rail A gives a distinctive appearance to the casket-top and casket irrespective of the particular design or form of the rail itself. The particular design of the rail-supporting posts B also may vary within the scope of my invention.

The herein-described design is particularly adapted for the tops of burial-caskets used for bodies lying in state during public funeral ceremonies, as the rail gives to the eye the impression of a guard-rail, which is very appropriate and effective.

Having thus described my invention, what I claim as new, and desire to secure by Letters Patent, is—

A design for casket-tops, consisting of a casket-top having posts upon its frame and a rail passing from post to post entirely around the casket-top, as shown and described.

WILLIAM J. NOBLE.
